UNITED STATES PATENT OFFICE.

HARRY H. HANCOCK, OF SWAMPSOFT, MASSACHUSETTS, ASSIGNOR TO HENRY A. SAWYER, OF LYNN, MASSACHUSETTS.

PRINTER'S QUOIN.

Application filed January 20, 1922. Serial No. 530,569.

To all whom it may concern:

Be it known that I, HARRY H. HANCOCK, a citizen of the United States, residing at Swampscott, in the county of Essex and 5 State of Massachusetts, have invented certain new and useful Improvements in Printers' Quoins, of which the following is a specification.

Heretofore printers' quoins have been 10 made in which the quoin comprises two side members which are adjustable by means of a wedge, the side members being provided with means for expanding and contracting the quoin by means of said wedge, and 15 with means for guiding the side members during the operation of expanding or contracting the quoin. Under the present invention, one of the objects is to make such a quoin as narrow as possible, the same being 20 suitably constructed as to the side members and the expanding screw as to render this possible. Another object is to avoid the necessity of especially constructing the wedge for the purpose of contracting the side members, 25 this being accomplished by the use of suitable springs, which are preferably concealed. Other objects are to provide a printer's quoin which is economically manufactured, and which is efficient in use. 30 These being among the objects of the present invention the same consists of certain features of construction and combinations of parts to be hereinafter described, and then 35 claimed with reference to the accompanying drawings illustrating a desirable embodiment of the invention, in which:

Fig. 1 is a perspective view of the improved quoin;

Fig. 2 is a plan;

Fig. 3 is a side elevation;

Fig. 4 is a plan, showing the quoin expanded; and

Fig. 5 is a transverse section on the line 5—5, Fig. 3.

45 The side members 10, 11 of the quoin are composed of suitable metal, and which may be die-cast or otherwise made into blocks or plates of suitable thickness. The side members are provided at the lower portions of 50 their inner faces with inclines 12 at the sides of longitudinal recesses in said members, and which flare away from each other, and against which inclined surfaces a wedge 13 is adapted to act.

55 The wedge 13 is provided with a screw-

threaded opening for receiving a screw-threaded stem 15 of a screw having a head 16. The head 16 is adapted to turn upon the side members 10, 11, and for the purpose of turning it it is provided with a preferably hexagonal socket 17, into which the head of a suitable wrench may be introduced.

Preferably, as shown, one of the side members carries a pin 18, while the other side member carries a pin 19, said pins being provided with annular shoulders or flanges 18^a, 19^a, respectively. When the side members are pressed together or contracted, so that the inner faces thereof are in contact, with the wedge in its lowermost position, the length of each pin 18, 19 is preferably equal to the combined widths of the side members. When each side member is provided with a pin such as 18, 19, the other side member is provided with a socket or bore 20, which is of just such diameter that the annular shoulder or flange on the pin may be guided snugly in its socket. The ends of the pins opposite the annular shoulders or flanges are driven with a drive-fit into suitable holes in the appropriate side member. Coiled around the pin 18, and located in the socket in the side member 11, is a helical expansion-spring 21, the ends of which bear respectively upon the bottom of the socket and against the annular shoulder or flange 18^a. A helical expansion-spring 22 is similarly arranged in the socket 20 of the side member 10.

At the midlength of each side member 10, 11 there is a cavity 23, which is preferably semi-circular so as to conform to the circularity of the head 16 of the adjusting-screw, the wider portions of these cavities meeting when the side members 10, 11 are in contact at their inner faces.

When the side members 10, 11 are in contact, the cavities 23, 23 form a circular concavity, in which the head 16 of the adjusting-screw fits neatly, said cavities being of such width transversely of the side members that the head 16 of the adjusting-screw may be as large as possible, and the width of the side members when in contact, as narrow as possible. This furnishes an ample bearing for the head of the screw upon the side members and reduces the amount of metal necessary in the quoin. As the side members are made as narrow as possible, and as the

width of the cavities 23 in each of them is made as wide as possible, so that the head 16 may be as large as possible, it is desirable that the cavities be open at the outside surfaces of the side members, which may be done by providing open recesses 24 extending from the cavities through the said surfaces of the side members. This furthermore enables the side members to be made as narrow as possible, and the head of the screw as large as possible. Preferably, the cavities 23, 23 are of such depth that the head of the screw will be countersunk therein.

15 When a suitable wrench is inserted in the socket 17 in the head of the screw and turned in proper direction, the quoin may be expanded from its contracted position shown in Fig. 2 to its extreme expanded position shown in Fig. 4. During this operation the wedge 13 is moved upwardly against the inclined surfaces 12, 12 of the side members, and the quoin is expanded. When the wrench introduced into the socket 17 is turned in reverse direction, the wedge itself does not act to contract the quoin, but the springs 21, 22, which were contracted during expansion of the quoin, will themselves act automatically to contract the quoin due to their expansion. So that during the contraction of the quoin, the guide means for the side members, assisted by the springs, will actually contract the quoin, for then the adjusting-screw will be acting to position the wedge downwardly.

In the preferred form shown, it is clear that the wedge merely acts to expand the quoin, while the springs merely act to contract the quoin, both actions being dependent upon the turning of the adjusting-screw one way or the other in the wedge, so that the quoin as a whole is exceedingly simple and comparatively inexpensive. This action is made possible because the ends of the wedge do not interlock or interengage with the side members.

It is obvious that the invention is susceptible to modification without departing from the spirit and scope thereof, as defined in the claims.

What I claim as new is:

1. In a printer's quoin, the combination of side members having inclined inner faces, which flare towards one side of the quoin, a wedge bearing on said faces and having a screw-threaded opening, a headed screw engaged in said opening, the side members

having cavities at the opposite side of the quoin in which the head of the screw is countersunk, and said cavities being open to the two remaining sides of the quoin, and the screw-head being approximately the width of the side members when they are contracted, and guide means for the side members during their expansion and contraction.

2. In a printer's quoin, the combination of side members having inclined inner faces, which flare towards the bottom of the quoin, a wedge bearing on said faces and having a screw-threaded opening, a headed screw engaged in said opening and the head bearing on the top of the quoin to merely expand it, guide means for the side members during their expansion and contraction, and expansion springs arranged to act on said guide means to merely force the side members towards each other when the wedge is released therefrom, the wedge and the side members being free from interlock or interengagement at the ends of the wedge.

3. In a printer's quoin, the combination of side members having longitudinal recesses, a wedge bearing on the side walls of the recesses for expanding said side members, the ends of the wedge and the ends of the said recesses being free from mutual interlock or interengagement, and a guide-pin carried by each of said side members, and each of said members having a socket for the said pins to move in.

4. In a printer's quoin, the combination of side members having inclined inner faces, which flare towards one side of the quoin, a wedge bearing on said faces and having a screw-threaded opening, a headed screw engaged in said opening, the side members having cavities at the opposite side of the quoin in which the head of the screw is countersunk, and said cavities being open to the two remaining sides of the quoin and the screw-head being approximately the width of the side members when they are contracted, a guide-pin carried by each of said members, said guide-pins having abutments located at opposite sides of the quoin, and each of the members having an enlarged open-ended socket for the abutments to move in, and helical expansion springs around said pins, located in said sockets and seated on the closed ends of said sockets and on said abutments in order to contract said members.

HARRY H. HANCOCK.
